ACCELERATOR MECHANISM

Frank J. Hansen, Cheyenne, Wyo., assignor of
one-half to James C. Valentine, Sioux City,
Iowa

Application July 27, 1937, Serial No. 155,971

4 Claims. (Cl. 137—139)

This invention relates to an accelerator mechanism to be employed with a throttle valve control means forming the subject matter of my copending application filed June 15, 1936 and 5 Serial No. 85,367, now Patent No. 2,136,295, of Nov. 8, 1938, and has for the primary object the provision of a mechanism of this character which after the adjustment of the throttle valve control means to permit running or operating of 10 an engine at variable speeds from idling speed to a selected or predetermined speed will permit a temporary increase or full speed of operation of said engine to meet emergencies or similar requirements over the selected speed and which 15 will automatically decrease the engine speed from its maximum speed to the selected speed within a predetermined period of time.

With these and other objects in view, this invention consists in certain novel features of construction, combination and arrangement of parts 20 to be hereinafter more fully described and claimed.

For a complete understanding of my invention, reference is to be had to the following description and accompanying drawing, in which

Figure 1 is a fragmentary side elevation illustrating a motor vehicle engine equipped with an accelerator mechanism constructed in accordance with my invention and showing the same 30 connected with the throttle valve control means.

Figure 2 is a fragmentary vertical sectional view illustrating a dash pot.

Figure 3 is a fragmentary vertical sectional view illustrating the throttle valve control means.

Figure 4 is a sectional view taken on the line 4—4 of Figure 3.

Referring in detail to the drawing, the numeral 1 indicates an internal combustion engine of a motor vehicle, 2 the carbureter and 3 the 40 throttle valve of said carbureter. The throttle valve is provided with an arm 4 to which my invention is connected.

The throttle valve control means heretofore referred to is indicated in entirety by the character 45 5 and is mounted on the instrument board of the motor vehicle in convenient reach of the operator and consists of a cylinder 38 in which a stem 42 extends and the latter has secured to its outer end a finger piece 43 and to its inner 50 end a disc-like member 44. A clutch operating piston-like member 45 is secured on the stem 42 and is of a diameter slightly less than the internal diameter of the cylinder 38. Located in the cylinder is a head 46 consisting of sections 47 and 48 providing therebetween a lim-

ited slide space 49 in which is received the disc-like member 44 of the stem. The space 49 permits the stem to have a limited movement with respect to the head 46. Clamped between the sections of the head 46 is a clutch plate 50, the periphery of which has peripheral contact with the internal walls of the cylinder. The clutch plate is slotted inwardly from its periphery, as shown in Figure 4, and is also dished, the purpose of which is to dispose the clutch plate at 10 a slight inclination when mounted on the head. The section 47 of the head has a flexible element 33 connected thereto and extends through a flexible tube 34, one end of which is connected onto the cylinder. The clutch plate will permit 15 the stem 42 to slide freely to the left in Figure 3. A movement of the head 46 in an opposite direction is prevented by the clutch plate biting against the internal walls of the cylinder. The throttle valve control means heretofore briefly 20 described forms the subject matter of the copending application herein referred to and is merely set forth in the present application to show its use in conjunction with the present invention.

Any of the other forms of throttle valve control means set forth in the copending application may be used in conjunction with the present invention.

A supporting bracket 53 is located adjacent 30 the carbureter 2 and pivotally supports a bell crank lever 54, one end of which is connected to an accelerator pedal 55 through links and levers indicated generally by the character 56. The other end of the bell crank lever 54 is pivotally connected to a dash pot mechanism 56 and the latter is connected to the arm 4 of the control valve 3. A coil spring 54' is connected to one of the rods employed for connecting the bell crank lever 54 to the accelerator pedal and 40 acts to urge the throttle valve into a substantially closed position for obtaining idling speed of the engine. A stop 52 is adjustably mounted on the bracket 53 and has the flexible element 33 connected thereto. The stop 52 may be adjusted along said bracket 53 for limiting the 45 pivotal movement of the bell crank lever 54 in one direction or in a direction to open the control valve 3. The dash pot mechanism 56 consists of a cylinder 58 in which operates the piston 59 of the cup type defining between itself and one end of the cylinder an air chamber 60. A pipe 61 is connected with the chamber 60 and is threaded into a head 62 having a vent opening 63 and a valve seat 64. The valve seat 64 55

communicates with the vent opening 63 and also with the pipe 61. One end of the pipe is shaped to conform to the valve seat 64. The head 62 is adjustably connected on a rod 66 which is pivoted on the arm 11. The stem of the piston 59 is indicated by the character 67 and extends exteriorly of the cylinder. A head 68 carried by the cylinder slidably supports the stem 67 and is provided with vent openings 69. The stem 67 is further slidably supported by a web 70 slidably mounted in the cylinder. The web is fixed to move with the stem and has connected thereto one end of a coil spring 71, the other end of the spring being secured to the head 68. The 15 spring 71 is weaker than the spring 54. The stem 67 is connected to a turn buckle 72 and the latter is connected to a rod 73 which is pivoted on one end of the bell crank lever 54. By adjusting the head 62 in the pipe 61 the 20 flow of air into and out of the air chamber 60 may be regulated.

In operation, the operator or driver after setting the stop 52 by the throttle valve control means 5 for the selected speed may increase the 25 speed of the engine over said selected speed for a temporary period of time by taking the foot off of the accelerator pedal 55, permitting the spring 54 to return the valve 12 to idling speed and then again pressing the accelerator pedal 55, 30 which through the dash pot mechanism will move the valve 3 to its maximum open position. This is accomplished by the air being partially trapped between the piston 59 and one end of the cylinder within said air chamber 60 to temporarily 35 increase the throw from the accelerator pedal to the throttle valve 12. The escape of the air from the chamber 60 is gradual by way of the vent opening 63. As the air escapes from the chamber 60 the spring 71 moves the cylinder 58 40 to the left in Figure 2 until the inner end of the pipe 61 abuts the piston 59. This movement of the cylinder 58 relative to the piston draws the valve 12 towards a closed position reducing the speed of the engine to the selected speed set by 45 the throttle valve control means 5. Thus it will be seen that the maximum speed of the engine is automatically decreased to a selected speed within a predetermined length of time.

What is claimed is:

50 1. In combination with the throttle valve of

an engine, a manually actuated control, an operating connection between the manually actuated control and the throttle valve, means cooperable on said operating connection for limiting the opening travel of the throttle valve, and means interposed in said operating connection and actuated by the same for temporarily opening the throttle valve beyond the limits of said means. 5

2. In combination with the throttle valve of an engine, a manually actuated control, an operating connection between the manually actuated control throttle valve, means cooperable on said operating connection for limiting the opening travel of the throttle valve, and means interposed in said operating connection and actuated by the same for temporarily opening the throttle valve 10 beyond the limits of said means, said second means comprising an air trap having a restricted air bleed to the atmosphere. 15

3. In combination with the throttle valve of an internal combustion engine, an accelerator 20 pedal, a bell crank pivotally mounted on a fixed support, an operating connection between one end of the bell crank and the accelerator pedal, an operating connection between the other end of 25 the bell crank and the throttle valve, an adjustable stop arranged in the path of the bell crank for limiting the pivotal action thereof, to stop the throttle valve in a predetermined open position, and means interposed in said second 30 operating connection operated through adjustment of the bell crank for temporarily opening the throttle valve beyond the limits of said stop. 35

4. In combination with the throttle valve of an internal combustion engine, an accelerator 40 pedal, a bell crank pivotally mounted on a fixed support, an operating connection between one end of the bell crank and the accelerator pedal, an operating connection between the other end of 45 the bell crank and the throttle valve, an adjustable stop arranged in the path of the bell crank for limiting the pivotal action thereof, to stop the throttle valve in a predetermined open position, and means interposed in said second operating connection operated through adjustment of the bell crank for temporarily opening the throttle valve beyond the limits of said stop, said means comprising an air trap having a restricted air bleed to the atmosphere. 45
